UNITED STATES PATENT OFFICE.

HARVEY HUESTIS, OF PROVIDENCE, RHODE ISLAND.

DESIGN FOR A FINGER-RING.

SPECIFICATION forming part of Design No. 14,967, dated April 22, 1884.

Application filed March 10, 1884. Term of patent 7 years.

To all whom it may concern:

Be it known that I, HARVEY HUESTIS, of the city and county of Providence, State of Rhode Island, have invented a new and original Design for Ornamental Finger-Rings; and

5 I hereby declare the following to be a full, clear, and exact description of the same, reference being had to the accompanying drawing, forming part of this specification.

10 The drawing is an enlarged view of my newly-designed ornamental center for finger-rings, showing the union of the band with the central setting.

15 Rings to be worn for ornament have heretofore been variously ornamented at the union of the band forming the ring with the central setting, usually with scroll-work, such ornamentation merging into and forming part of the center into which the stone or jewel is set.

20 The leading feature of my design consists in a number of bars projecting from a raised curved band and spread fan-shaped to hold the center, which is surrounded with a blocked border.

25 In the drawing, A is the setting; B, the border of the setting formed into square blocks; C C, the band forming the ring.

D D are a number of bars radiating from

the raised and curved band E, so as to give them a fan-shaped appearance. The bars D 30 D are rounded at the ends, near the central setting. Five of these bars are shown in the drawing.

Below the curved band E a triangular ornament, g, separated from the band E by a 35 row of beads, f, is placed the apex of the triangular ornament ending in the pyramidally-placed leaves h, the whole presenting a fan-shaped appearance at the union of the ring-band with the central setting, producing 40 with the blocked setting a novel and agreeable effect.

Having thus described my invention, I claim as new and desire to secure by Letters Patent—

The design for ornamental finger-rings here- 45 in shown and described, the same consisting of the setting A, surrounded by the blocked border B, the bars D D, extending radially from the raised bands E E toward the central setting, and the pointed ornamentation f g h, 50 forming fan-shaped ornamentations at the union of the ring with the setting.

HARVEY HUESTIS.
